UNITED STATES PATENT OFFICE.

ROBERT C. BLOOD, OF PHILADELPHIA, PENNSYLVANIA.

SEAMLESS HOSIERY.

No. 800,840.

Specification of Letters Patent.

Patented Oct. 3, 1905.

Application filed March 22, 1905. Serial No. 251,427.

To all whom it may concern:

Be it known that I, ROBERT C. BLOOD, a citizen of the United States, residing at Philadelphia, in the county of Philadelphia and 5 State of Pennsylvania, have invented certain new and useful Improvements in the Manufacture of Seamless Hosiery; and I do hereby declare the following to be a full, clear, and exact description of the invention, such as 10 will enable others skilled in the art to which it appertains to make and use the same.

My present invention relates to improvements in the manufacture of hosiery, and more particularly to that class of articles known as 15 "seamless stockings;" and it consists in certain changes whereby a more perfectly fashioned stocking is produced.

In the drawings I have illustrated the principal points which constitute my improvement, and my said invention is disclosed in 20 the following description and claims.

Figure 1 is a side view of a portion of a stocking embodying my said improvement. Fig. 2 is a view of the back of the portion of 25 the stocking embodying my invention. Fig. 3 is a sectional view of the leg of the stocking, taken on line *xx* in Fig. 2 before the floated threads are removed. Fig. 4 is a like view 30 after cutting away the floated threads. Fig. 5 is a diagram of the threads in the double-knitted portion.

Seamless stockings are usually knit upon circular-knitting machines and in which the same number of stitches are employed 35 throughout. Various changes have been suggested by which the tubular web may be formed so as to taper the leg from the calf down to give the proper size to the ankle and make the stocking resemble "full-fashioned" stockings or stockings knit on straight machines, in 40 which the web is narrowed and a less number of stitches are employed in each knitted course in the ankle than in the calf of the stocking. One of these modes of shaping or fashioning 45 the stocking is by reducing the size of the stitch to effect the size of the knitted tube. Another is to use a smaller and finer thread in the part of the stocking which it is proposed to make smaller.

50 My mode of proceeding to reduce the size of the tube at the point desired is to reduce the size of the stitches in a less pronounced degree than is usually done and to throw in for the required distance a finer thread for 55 every other course of stitches interknitting the two threads for a given number of stitches

at the back of the leg and ankle of the stocking.

In knitting the stocking, as shown in Figs. 1 and 2, the stocking is knit in the usual way 60 of uniform size, beginning at the top, down to about the point *a*, where the stitch is slightly shortened. At the point *a'* a smaller or finer thread is thrown in, as at 2 in Fig. 5, and the two threads are knitted together for several 65 stitches, generally about five or six in number. The main thread 1 is then thrown out or carried toward the center of the tube and the ensuing course is knitted from the finer thread 2. As the thread-guides are again 70 brought to the point at which the thread 2 was thrown into the web thread 1 is again brought into position to be taken by the needles, and the two threads are again interknitted for the same number of stitches as 75 before. Thread 2 is then thrown out in the same manner and the operation repeated down to the point *a'* on the ankle of the stocking, when thread 2 is entirely dispensed with and the heel and foot made in the ordinary manner. 80 This interknitting of the thread forms the thickened piece *b*, in which a greater amount of thread is taken up than in plain knitting, and this serves to further reduce the size of the tube and assists in fashioning the 85 stocking. While this thickened piece *b* is being knit the length of the stitches may be further reduced if it is deemed best to do so. The thickened piece *b* serves to give shape to 90 the ankle of the stocking and to maintain its 95 fashioned form. The piece *b* being more rigid than other parts of the ankle keeps the form given it and maintains the shape of the stocking at that point. The introduction of the finer thread in every alternate course 100 aids in reducing the size of the tube, while the presence of the usual thread in alternate courses serves to prevent the web from becoming perceptibly lighter. Thus the entire leg of the stocking when completed appears 105 to be homogeneous throughout with the exception of the thickened part *b*.

In Fig. 3 the floated threads are shown at the conclusion of the knitting operation. In order to insure the proper tension of the floated threads, I prefer to employ a thread-retainer, composed of wire or some equivalent thereof, depending near the center of the cylinder, which will catch the thread from each guide and maintain the tension of the thread. 110 This wire or depending part extends downward for a little distance below the top of the

needle-cylinder, so that as the web descends these floated threads are drawn from the retainer. In finishing the stocking the floated threads are cut away near the web, leaving 5 short ends, as shown at *c* in Fig. 4.

While I have described the stocking having the ankle portion made from two threads, it is obvious that three threads of differing degrees of fineness might be employed, and if 10 in the view of the manufacturer it would be desirable one or more additional threads might be employed.

What I claim, and desire to secure by Letters Patent, is—

15 1. A machine-knit seamless stocking having the reduced portion of the leg composed

of two threads knit in alternating courses, said threads being interknit for a number of stitches, substantially as described.

2. A machine-knit seamless stocking having the ankle portion of the stocking reduced in size and formed by two or more threads of differing degrees of fineness in alternate courses and interknit for a short distance at the back of the stocking, substantially as described. 20 25

In testimony whereof I affix my signature in the presence of two witnesses.

ROBERT C. BLOOD.
